ANNULAR CUTTER FOR A SLICING MACHINE

Joe R. Urschel, 202 Michigan Ave., Valparaiso, Ind.

Filed Sept. 18, 1961, Ser. No. 66,739

Term of patent 14 years

(Cl. D55—1)

Fig. 1

Fig. 2

Fig. 3

FIGURE 1 is a perspective view of an annular cutter for a slicing machine showing my design;

FIGURE 2 is a side elevational view thereof; and

FIGURE 3 is a reduced top view thereof, with an upper portion of the cutter head being broken away to illustrate the cross sectional character of its columnar structure.

The columnar structure illustrated by the full lines in FIGURES 1 and 2 correspond throughout the annular extent of the cutter head.

I claim:

The ornamental design for an annular cutter for a slicing machine, as shown and described.
